ABSTRACT OF THE DISCLOSURE

Mirror bright zinc electrodeposits are formed from acid zinc plating solutions containing as brighteners N-polyvinylpyrrolidone-(2) and a ketone of the formula

wherein R_1 is phenyl, mono- or dihydroxyphenyl or trihydroxyphenyl methylenedioxyphenyl, mono-, di- or tri-lower-alkylphenyl, mono- or di- or tri-lower-alkoxyphenyl, furyl, thieryl, coumaryl, or pyridyl, and R_2 may be lower alkyl, lower alkenyl, lower-alkyl-carbonyl-lower-alkylene, cyano-lower-alkylene, lower-alkoxy-carbonyl-lower-alkylene, or $-(CH=CH)_n-C_6H_5$, n being 1 or 0.

This invention relates to the electrodeposition of bright zinc, and particularly to bright zinc plating from acid electrolytes.

A wide variety of bright zinc plating solutions of the cyanide type is available. The cyanide baths are relatively unstable because of the decomposition of cyanide to carbonate, and the cyanide drag-out into rinsing baths presents a serious disposal problem. The deposits formed from known acid zinc plating baths free from organic complexing agents are at best smooth, but not bright, and complex forming organic components in acid zinc plating solutions, such as EDTA present a disposal and pollution problem as difficult to solve as that caused by cyanide. Zinc and other heavy metals cannot be precipitated from the rinse water and other wastes bearing EDTA by means of alkaline reagents. Bright coatings can be produced from baths containing EDTA (ethylenediaminetetra-acetic acid) only if other heavy metals, particularly iron, copper, and nickel, are carefully and initially removed.

The object of the invention is the provision of a brightener system for acid zinc plating solutions which permits the zinc dragged out into rinsing baths to be precipitated by an alkaline reagent because of the absence of complex forming compounds, is insensitive to substantial amounts of other heavy metal, provides bright and ductile deposits over a wide range of cathode current densities, and is stable under the operating conditions usual for the electrodeposition of dull coatings from acid electrolytes including agitation by means of compressed air.

Such a brightener system has been found in the combination of N-polyvinylpyrrolidone-(2) with a secondary brightener of the formula

wherein R_1 is

EXAMPLE 2

Zinc sulfate ($ZnSO_4 \cdot 7H_2O$): 290 g./l.
 Ammonium chloride: 25 g./l.
 Polyvinylpyrrolidone-(2): 5 g./l.
 Propiophenone: 0.1 g./l.
 Nonylphenol-ethyleneoxide addition compound: 0.04 g./l.
 pH: 4.5
 Temperature: 30° C.
 Current density: 0.1-6.0 amps/dm.²
 Cathode rod agitation

EXAMPLE 3

Zinc chloride ($ZnCl_2$): 70 g./l.
 Ammonium sulfate: 130 g./l.
 Sodium chloride: 10 g./l.
 Polyvinylpyrrolidone-(2): 3 g./l.
 Benzalacetone: 0.1 g./l.
 Ethyl benzoylacetate: 0.1 g./l.
 Sodium ethylhexylsulfate: 0.5 g./l.
 pH: 5.0
 Temperature: 25° C.
 Current density: 0.1-5.0 amps/dm.²
 Air agitation

EXAMPLE 4

Zinc sulfate ($ZnSO_4 \cdot 7H_2O$): 145 g./l.
 Ammonium chloride: 53 g./l.
 Boric acid: 20 g./l.
 Polyvinylpyrrolidone-(2): 3 g./l.
 1-(2-Furyl)-1'-buten-3-one: 0.1 g./l.
 Nonylphenol-ethyleneoxide: 0.4 g./l.
 pH: 4.2
 Temperature: 25° C.
 Current density: 0.1-5 amps/dm.²
 Cathode rod agitation

EXAMPLE 5

Zinc sulfate ($ZnSO_4 \cdot 7H_2O$): 290 g./l.
 Ammonium chloride: 25 g./l.
 Polyvinylpyrrolidone-(2): 5 g./l.
 3-Acetylpyridine: 3 g./l.
 Fatty alcohol polyglycoether: 0.2 g./l.
 pH: 4.8
 Temperature: 30° C.
 Current density: 0.1-7.5 A./dm.²
 Cathode rod agitation

EXAMPLE 6

Zinc sulfate ($ZnSO_4 \cdot 7H_2O$): 145 g./l.
 Ammonium chloride: 53 g./l.
 Polyvinylpyrrolidone-(2): 2.5 g./l.
 1-(2-Furyl)-1'-buten-3-one: 0.2 g./l.
 Sodium dodecylphenol-polyglycol-ether-sulfate: 0.1 g./l.
 pH: 5.0
 Temperature: 25° C.
 Current density: 0.1-5 amps/dm.²
 Cathode rod agitation

EXAMPLE 7

Zincsulfate ($ZnSO_4 \cdot 7H_2O$): 145 g./l.
 Ammoniumchloride: 53 g./l.
 Boric acid: 20 g./l.
 Polyvinylpyrrolidone-(2): 3 g./l.
 3-methoxy-benzaleacetone: 0.15 g./l.
 pH: 5.5
 Temperature: 25° C.
 Current density: 0.1-5.0 A./dm.²
 Air agitation

EXAMPLE 8

Zinc sulfate ($ZnSO_4 \cdot 7H_2O$): 290 g./l.
 Ammoniumchloride: 25 g./l.

6

Polyvinylpyrrolidone-(2): 5 g./l.
 4-methoxy-benzylideneacetone: 0.05 g./l.
 Nonylphenol-ethyleneoxide addition compound: 0.04 g./l.
 pH: 4.5
 5 Temperature: 30° C.
 Current density: 0.1-6 amps/dm.²
 Cathode rod agitation

EXAMPLE 9

10 Zinc chloride ($ZnCl_2$): 70 g./l.
 Ammonium sulfate: 130 g./l.
 Sodiumchloride: 10 g./l.
 Polyvinylpyrrolidone-(2): 3 g./l.
 Piperonylideneacetylacetone: 0.2 g./l.
 15 Sodium ethylhexylsulfate: 0.5 g./l.
 pH: 5.0
 Temperature: 25° C.
 Current density: 0.1-5 amps/dm.²
 Air agitation

20 EXAMPLE 10

Zinc sulfate ($ZnSO_4 \cdot 7H_2O$): 145 g./l.
 Ammoniumchloride: 53 g./l.
 Boric acid: 20 g./l.
 Polyvinylpyrrolidone-(2): 3 g./l.
 25 Piperonylidenebenzylacetone: 0.1 g./l.
 Nonylphenol-ethyleneoxide: 0.4 g./l.
 pH: 4.2
 Temperature: 25° C.
 Current density: 0.1-5 amps/dm.²
 30 Cathode rod agitation

EXAMPLE 11

Zinc sulfate ($ZnSO_4 \cdot 7H_2O$): 145 g./l.
 35 Ammoniumchloride: 53 g./l.
 Polyvinylpyrrolidone-(2): 2.5 g./l.
 2-thienylideneaceton: 0.2 g./l.
 Sodium dodecylphenol-polyglycoether-sulfate: 0.25 g./l.
 pH: 4.8
 40 Temperature: 30° C.
 Current density: 0.1-5 amps/dm.²
 Cathode rod agitation

EXAMPLE 12

45 Zinc sulfate ($ZnSO_4 \cdot 7H_2O$): 290 g./l.
 Ammoniumchloride: 25 g./l.
 Polyvinylpyrrolidone-(2): 5 g./l.
 A-acetylcoumarin: 0.4 g./l.
 pH: 4.8
 50 Temperature: 30° C.
 Current density: 0.1-5 amps/dm.²
 Cathode rod agitation
 What is claimed is:
 1. In an aqueous acid plating electrolyte for the deposition of zinc electrodeposits in the absence of organic compounds forming complex ions with heavy metals, the electrolyte containing a source of zinc ions, the improvement which comprises having present in said electrolyte:
 55 (a) 0.5 to 100 grams per liter N-polyvinylpyrrolidone-(2) dispersed in said electrolyte as a primary brightener; and
 (b) .01 to 0.5 gram per liter of a secondary brightener dispersed in said electrolyte, said secondary brightener being a compound of the formula

wherein R_1 is

75 R_2 is lower alkyl, lower alkenyl, lower alkyl-carbonyl-

lower-alkylene, cyano-lower alkylene, lower-alkoxy-carbonyl-lower-alkylene, or

R_3 , R_4 and R_5 each are hydrogen, hydroxy, lower alkyl, or lower alkoxy, and R_3 and R_4 together represent the methylenedioxy group, and n is 1 or 0.

2. In an electrolyte as set forth in claim 1, the concentration of said N-polyvinylpyrrolidone-(2) being between 2 and 10 grams per liter, and the concentration of said secondary brighteners between 0.05 and 0.3 gram per liter.

3. In an electrolyte as set forth in claim 1, R_2 being methyl or ethyl.

4. In an electrolyte as set forth in claim 3, R_2 being ethenyl.

5. In an electrolyte as set forth in claim 1, R_2 being $-\text{CH}_2\text{COCH}_3$.

6. In an electrolyte as set forth in claim 1, R_2 being

7. In an electrolyte as set forth in claim 1, the pH being 3 to 6.

10 8. A method of forming bright zinc electrodeposits which comprises making an object the cathode in the electrolyte as set forth in claim 1.
